UNITED STATES PATENT OFFICE

WILLIAM RHEINER, OF DETROIT, MICHIGAN

LAMP FIXTURE

Application filed February 2, 1931. Serial No. 512,967.

This invention relates to a lamp fixture and refers more particularly to a fixture for an electric lamp or the like.

One of the primary objects of this invention is to provide a fixture of the above mentioned character which will be extensible to permit positioning of the lamp at variable distances from the support for the fixture.

10 The invention further contemplates the provision of a gravity actuated means for facilitating the positioning of the lamp and the provision of a fixture which will be simple in construction and yet thoroughly efficient in operation.

Numerous other objects and advantages of this invention will become more apparent as the following description proceeds, particularly when reference is had to the accompanying drawings, wherein:

Figure 1 is an elevational view showing a lamp fixture constructed in accordance with the teachings of this invention in both retracted and extended positions;

25 Figure 2 is an enlarged sectional view through a portion of the structure shown in Figure 1;

Figure 3 is a sectional view taken substantially on the line 3—3 of Figure 2;

30 Figure 4 is a sectional view taken substantially on the line 4—4 of Figure 2;

Figure 5 is an enlarged sectional view through another portion of the device shown in Figure 1; and

35 Figure 6 is an enlarged sectional view similar to Figure 5 but showing a slightly modified form of construction.

Referring then particularly to the drawings, there is shown in Figure 1 a lamp fixture which includes the lamp bulbs 10 supported by arms 11 which extend laterally from a housing 12. This housing is in turn supported from the ceiling 13 of a room or the like for movement from the position shown in full lines in Figure 1 of the drawings to the position shown in dotted lines therein. It is to be understood that while two arms 11 are shown as projecting from the housing 12, any number of arms may be arranged to project from this housing and

these arms may be shaped in any desired manner to give the desired appearance to the fixture.

For supporting the housing 12 while providing for movement of the same in the above mentioned manner, the structure more clearly shown in Figures 2 to 5, inclusive, is provided. By reference then to these figures it will be noted that a plate 15 is fixed by screws or the like 16 to the ceiling 13 or to any other suitable support. This plate is provided centrally with the aperture 17 to permit the passage therethrough of electric conduits 18 and is provided at a plurality of points around the aperture 17 with the depending lugs or projections 19. Secured to these projections as by the bolts 20 is a plate 21 provided with a centrally arranged depending tubular projection 22. The spaced relation of the plate 21 from the plate 15 provides a chamber 23 for receiving the slack in the conduits 18 which is necessary to provide for the ready attachment of these conduits to contacts, as will hereinafter be more fully described.

By reference to Figures 3 and 4 of the drawings, it will be noted that the member 22 is substantially square in cross section and fitted in this member is one end of a tubular member 24 which is likewise substantially square in cross section. The member 24 extends downwardly to a point a substantial distance below the plate 21 and is preferably formed of metal and is externally plated to provide a pleasing appearance.

Fitted in the upper end of the member 24 are a pair of insulating blocks 25 and 26, these blocks being preferably held together by a bolt or the like 27. These insulator blocks support a pair of tubular contact members 28 and 29 to which the ends of the electric leads 18 are connected. Bolts 30 are threaded through the member 22 and the upper end of the member 24 and engage the block 25 to hold these members in assembled position as will be readily apparent.

Threaded in the lower ends of the contact members 28 and 29 are contact rods 30 and 31 which are provided adjacent their lower ends with the enlarged portions 32. Sleeves

33 of insulating material are preferably mounted on the reduced portions of the rods 30 and 31 to prevent short-circuiting in the event that these members become twisted and 5 contact with each other.

Telescopically mounted within the tubular member 24 is a tubular member 35 which is preferably circular in cross section, as clearly illustrated in Figures 3 and 4 of the drawings. At its ends this member is provided with the insulating blocks 36 and 37 which support within the tubular member 35 and in spaced relation to each other, metallic tubes 38. These tubes are preferably provided 15 on their outer peripheries with the insulating sleeves 39 and are provided at their lower ends with the contacts 40 which are connected to electrical leads 41.

The tubes 38 are so arranged as to slidably 20 receive the enlarged ends 32 of the rods 30 and 31, the arrangement being such that the portions 32 of the rods are mounted for sliding movement within the tubes but have electrical contact with the inner peripheries 25 thereof. Thus the enlarged portions 32 of the rods provide an electrical connection between the conduits 18 and the tubes 38, and thus provide for the supplying of electrical current to the leads 41. Thus it will be apparent 30 that at any position of the telescopic movement of the member 35 in the member 24, the electrical leads 18 will be electrically connected to the leads 41.

Fixed to the plate 21 and depending from 35 the same are supports 50 and journaled in these supports are pulleys 51. These pulleys mount a pair of chains 52 and one end of each of these chains is anchored to the upper edge of a cup-shaped member 53 which is 40 slidably mounted on the tubular member 24. The cup-shaped member is provided with a pair of tubular guides 54 through which the other ends of the chains pass, and these ends of the chains are connected to the lower end 45 of the member 35 in a manner which will hereinafter be more fully described.

The member 53 provides means for counter-weighting or balancing the lamp fixture carried by the lower end of the member 50 35. The member 53 being cup-shaped provides a chamber 55 in which weights or the like (not shown) may be positioned so that the effective weight of this member may be varied to give the desired balancing effect. 55 If desired, a suitable cover 56 may be provided for the top of the cup-shaped member 53 while an escutcheon plate 57 is preferably fixed to the ceiling 13 in a position to enclose the pulleys 51 and the supporting plates 15 and 21.

Fixed to the lower end of the member 35 as by the bolts 60 are angle members 61 and these members are slotted as at 62 to provide for the anchoring of the chains 52 to the 60 same. Thus any link of each chain may be

hooked to its respective member 61, this form of connection providing for adjustable connection of the chains to the member 35, as will be readily apparent.

The bolts 61 also secure to the lower end 70 of the member 35 a bushing 65 which projects upwardly from a housing 66 which is provided with openings 67 for receiving the ends of the arms 11. The leads 41 extending from the tubes 38 may thus be divided and extended 75 through the openings 67 in the arms 11 for electrical connection to the lamps 10, as will be readily apparent. The housing 12 provides means for enclosing the housing 66, and is provided with the openings 68 to permit the passage therethrough of the chains 80 52.

The tubular member 24 is provided adjacent its upper end with a plurality of openings 70 which communicate with the atmosphere to prevent the creation of a pneumatic cushion or a vacuum in the member 24 upon the reciprocation of the member 35 in this member while the tubular members 38 are likewise provided with similar openings 71 90 for the same purpose. The member 35 is further provided adjacent its upper ends with the laterally extending lugs 72 which are positioned in the corners of the member 24 and which constitute stops engageable with the lower end of the member 24 to limit longitudinal movement of the member 35.

In operation, the member 53 is weighted sufficiently to substantially balance the 100 weight of the lamp bulbs and supporting arms fixed to the end of the member 35. Thus the housing 12 together with the supporting arms and lamp bulbs carried by this housing, may be moved upwardly to the position shown in full lines in Figure 1 of the drawings and will be held in this position by the weight of the member 53 and the weights therein acting through the chains 52. Obviously, the housing 12 and associated lamps may also be moved downwardly to the position shown in dotted lines in Figure 1 of the drawings or to any intermediate position as desired. The enlarged portions 32 of the rods 30 and 31, sliding within the tubes 38 and being in electrical engagement with these tubes, provide means for electrically connecting the leads 18 to the leads 41 in any position of the housing 12 with the result that regardless of extension or retraction of the supporting fixture, electric current will be supplied to the lamp bulbs.

In the above embodiment of the invention, the supporting fixture is shown as supporting a plurality of lamp bulbs. It will be readily apparent, however, that the invention will find equal utility in supporting a single lamp bulb or socket, as clearly illustrated in Figure 6 of the drawings. By reference to this figure it will be noted that the bolts 61' 125 secure to the lower end of the tube 35 the up- 130

per half 80 of a lamp socket. The lower portion 81 of the lamp socket is threaded in the usual manner to receive a lamp bulb and is provided with the contacts 82 to which the 5 leads 41' are electrically connected.

For securing the two halves of the lamp socket to each other, the upper half is preferably provided with the tubular members 83 adapted to receive bolts 84 which are 10 threaded in extensions 85 formed on the lower half of the socket member. Thus the two halves of the socket member may be firmly and quickly secured to each other without the exertion of a torque or turning force on 15 the tube 35'.

From the above it will be apparent that the invention provides a supporting fixture for lamp bulbs, which fixture is extensible to provide for the movement of the lamp bulbs 20 toward or away from the wall or support to which the supporting fixture is secured. The invention provides slideable contacts for assuring an electrical connection between the leads and the lamp bulbs and provides means 25 for counterbalancing the weight of the lamp bulbs so that these lamp bulbs may be held in any intermediate extended position.

While the invention has been described as being associated with a supporting fixture 30 which is secured to a ceiling or the like, it will be readily apparent that the inventive principles may be incorporated in a desk lamp or the like, in which event the plate 15 or a similar member will be connected to 35 a suitable supporting standard or the like. The right is therefore reserved to make all such changes in the details of construction and arrangement of parts as will fall within the purview of the attached claims.

40 What I claim as my invention is:

1. In a device of the character described, a supporting plate, a tubular member fixed to said supporting plate and projecting downwardly therefrom, a second tubular member 45 mounted for sliding movement within said first mentioned tubular member, a lamp bulb carried by said second mentioned tubular member, electrical leads passing through said supporting plate, electrical leads for said 50 lamp bulb, means for electrically connecting said first mentioned leads to said second mentioned leads irrespective of movement of said tubular members relative to each other, said means including a pair of rods connected to 55 said first mentioned leads and tubular members connected to said second mentioned leads for telescopically receiving said rods, a counterweight slideable on said first mentioned tubular member, and a connection between 60 said counterweight and said second mentioned tubular member whereby said counterweight balances the weight of said second mentioned tubular member and the lamp bulb supported thereby.

65 2. In a device of the character described, a

supporting plate, a tubular member fixed to said supporting plate and projecting downwardly therefrom, a second tubular member telescopically engaging said first mentioned tubular member, a lamp bulb carried by said second mentioned tubular member, electrical contacts carried by said tubular members and telescopically engaging each other for electrically connecting said lamp bulb to a source of electric energy, a cup-shaped member slidably mounted on said first mentioned tubular member and adapted to receive a plurality of weights, pulleys carried by said supporting plate, and flexible members secured to said cup-shaped member and passing over said pulleys and being connected at their other ends to said second mentioned tubular member whereby the said cup-shaped member and the weights therein counterbalance the weight of said second mentioned tubular member and the lamp bulb carried thereby.

3. In a device of the character described, a supporting plate, a tubular member fixed to said supporting plate and projecting downwardly therefrom, a second tubular member telescopically engaging said first mentioned tubular member, a lamp bulb carried by said second mentioned tubular member, electrical contacts carried by said tubular members and telescopically engaging each other for electrically connecting said lamp bulb to a source of electric energy, a cup-shaped member slidably mounted on said first mentioned tubular member and adapted to receive a plurality of weights, pulleys carried by said supporting plate, slotted members fixed to the lower end of said second mentioned tubular member, and chains connected to said cup-shaped member and passing over said pulleys and adapted to be adjustably connected to said slotted members whereby said cup-shaped member and the weights therein counterbalance the weight of said second mentioned tubular member and the lamp bulb supported thereby.

4. In a device of the character described, a supporting plate, a tubular member fixed to said plate and projecting downwardly therefrom, a second tubular member telescopically engaging said first mentioned tubular member, a lamp bulb support carried by said second mentioned tubular member, a pair of current carrying rods connected to and insulated from said supporting plate extending downwardly within said first mentioned tubular member, a pair of tubular electrical contact members electrically connected to said lamp bulb support arranged within said second mentioned tubular member, said current carrying rods having enlarged portions electrically contacting with the inner peripheries of said tubular members and slideable therein, a weighted cup shaped member slidably mounted on said first mentioned tubular member, pulleys carried by said supporting

plate, chains secured to the periphery of said cup shaped member passing over said pulleys and downwardly through openings in said cup shaped members to the lamp bulb support, and connections between said chains and lamp bulb support providing for adjustment of said chains relative to said support.

In testimony whereof I affix my signature.

WILLIAM RHEINER.
